BENJAMIN E. BRONSTON, OF PLAINFIELD, NEW JERSEY

FLEXIBLE STRAW HAT

Application filed February 5, 1929. Serial No. 337,563.

My present invention relates to stiff straw hats and especially to those having a flexible head conforming portion intermediate the crown and the brim.

A defect of this type of straw hat lies in the weakness of the joint between the straw of the stiff portions and that of the flexible portion. It is usual to make the crown and brim of the hat out of what is known in the trade as sennit or rustic braid, which presents a saw-toothed edge at the finished side or sides. Now, obviously, the stitch connecting the stiff braid to the flexible braid has therefore, at numerous points, insufficient backing, and in view of the considerable flexure at the joint, the thread has a tendency to work through to the edge of the stiff braid at points and the sewing becomes undone.

It is therefore the main object of my invention to provide a simple structure to remedy this defect and to provide a sturdy straw hat with a flexible head-conforming portion.

This and other objects which will become apparent hereinafter, I achieve by introducing between the crown and the flexible portion, a section of stiff straw having a double straight smooth edge which can be sewed to the flexible portion strongly enough to resist the strain and can be sewed to the crown in the ordinary fashion.

Furthermore, instead of sewing together the edges of the brim and the flexible portions, I extend the flexible portion in between the plies of the brim clear to the outer edge of the latter, thus having a considerable area of engagement which can be sewed together in the ordinary manner.

I have shown in the drawings, and will now describe, an embodiment of my invention, but it is to be understood that various changes and alterations may be made therein without departing from the spirit of my invention or the scope of my claims.

In the drawings:

Figure 1 is a perspective view of a hat constructed according to my invention.

Figure 2 is an elevation of the hat of Figure 1, only so much being shown as is necessary to illustrate the invention.

Figure 3 is a plan view of the portion shown in Figure 2.

Figure 4 is a section along the line 4—4 of Figure 2.

The straw hat of my invention comprises a stiffened crown 1, a stiff brim 2, a flexible head conforming portion 3, intermediate the brim and the crown, and a stiff straw insert 4, connecting the crown 1, and the flexible portion 3. My hat may also be provided with the usual inner lining 5, sweat band 6, and outer band 7.

As usual the brim is made of several plies to give additional stiffness and strength. I have shown two plies 2', 2'' of rustic straw.

The flexible portion 3, may be made of braid known in the trade as "rumilage", has an upstanding crown portion 3a and a horizontal brim portion 3b extending the full width of the brim and running in between the stiff plies 2', 2''. An additional ply 3c of "rumilage" may be used to parallel the ply 3b. The plies 2', 3b, 3c, 2'' are then sewed together in the usual manner.

The crown, which is only conventionally represented, is made of "rustic" straw braid, sewed together by the usual "invisible stitch" (not shown) similar to the stitch 8. Intermediate the flexible portion 3a, and the crown 1, I have provided a stiff insert 4, made of a braid which is known to the trade as "flat foot rustic." This braid has at its finished side a smooth, sturdy edge shown at 9, in Figures 2 and 4. The insert 4, is secured to the flexible section 3a by means of a continuous chain stitch 10, parallel to the edge 9, and to the crown 1, by the ordinary "invisible stitch" 5.

Inherently the braid out of which the insert 4, is made, is stronger than the braid of the crown. The straight edge of section 4, is substantially a doubled edge all along its length, and the fibre of the straw runs at an angle to the edge. This straw therefore offers considerably more resistance to tearing out of the stitch than does the rustic or sennit of the crown. Since the insert is stiff and is stitched to the crown, the stresses and strains due to flexure at the stitch 10, are distributed over the entire crown and produce no except-

tional strain at the stitch 8. In use, the band 7, covers and conceals the portions 3a and 4, thus retaining the conventional appearance.

I claim as my invention:

5 1. A straw hat comprising a stiff crown, a brim, an intermediate flexible head-conforming member having a straight edge, and a stiff insert connecting the crown and the flexible portion, said insert being braided to 10 present a straight edge, the meeting edges of said insert and flexible member being straight.

15 2. In a straw hat having a stiff crown and a flexible head-conforming portion having a straight edge, a stiff insert intermediate and connecting the crown and the flexible portion, said insert being braided to present a straight edge, the meeting edges of said insert and flexible portion being straight.

20 3. Signed at New York, New York, in the county of New York and State of New York, this 31st day of January, A. D. 1929.

BENJAMIN E. BRONSTON.
